UNITED STATES PATENT OFFICE.

FREDERICK A. LEDWARD, OF FLINT, MICHIGAN.

CONCEALED DOOR-HINGE.

1,076,435.

Specification of Letters Patent. Patented Oct. 21, 1913.

Application filed January 27, 1913. Serial No. 744,382.

To all whom it may concern:

Be it known that I, FREDERICK A. LEDWARD, a citizen of the United States, residing at the city of Flint, in the county of 5 Genesee and State of Michigan, have invented a new and useful Concealed Door-Hinge, of which the following is a specification.

My invention relates to improvements in a concealed door hinge to be used on automobile doors more particularly, in which the hinge consists of two parts, male and female, anchored to the door and post respectively and engaging each other without a separate pin, and so constructed that the hinge is 10 concealed from observation when the door is closed. I attain these objects by the mechanism illustrated in the accompanying drawing, in which—

Figure 1 the hinge parts, male and female 20 separated; Fig. 2, the hinge assembled and the door open; dotted lines show position of female part when hinge is closed; Fig. 3, side view of both parts, male and female; Fig. 4, face view of both parts.

Similar letters refer to similar parts 25 throughout the several views.

The hinge comprises the members *a* and *d*, the former preferably attached to the jamb *Y*, and the latter attached to the door *X* by 30 screws as usual. The member *a* is fashioned with an integral plate *b* projecting at right angles therefrom, and this plate is seated in a recess provided therefor in the edge of the jamb *Y* when the plate is attached in place 35 on the jamb.

In the member *a* a vertically arranged perforation or socket *c* is formed, and the member is also formed with an L-shaped slot or opening *h*. At the side of the member *a* which becomes the inner side thereof when the member is in position, a reinforcing lug *g* projects, and this lug is flush with 40 one of the upper walls of the slot *h* and directly above the plate *b*.

The member *d* has projecting at right angles therefrom an integral angle plate *e* 45 from which depends a lug or boss *f* adapted

to seat in the socket or perforation *c* in the plate *b*, and a shoulder *e'* is formed integral with the plate *e*, and this shoulder, when the door is opened to its greatest width, holds the door open. A reinforcing lug *g* projects from the inner face of the member *d* just above the horizontal portion of the slot *h* and flush with the upper wall thereof, and 55 this lug guides or furnishes a bearing for the plate *b* as it swings in and out of the slot *h*.

The hinge members are attached to the jamb and door with screws as usual, the 60 jamb being recessed to receive the plate *b*. The door is hung while in full open position (Fig. 2) by holding up the door so that the boss *f* and angle plate *e* will pass through the L-shaped slot *h*. The boss is then inserted into the perforation or socket *c* in 65 plate *b* and becomes the pivot of the hinge. It will be understood of course that I use a plurality of hinges on a door, the number being determined by the circumstances of 70 the case. When the door is swung open or closed the plate *e* freely passes through the slot *h* swinging on the pivot bosses.

To remove the door it is opened full width, lifted to withdraw the bosses from 75 their sockets, and then the plate *e* and its boss are withdrawn through the respective slots *h*.

Having thus fully described my invention, what I claim as new and desire to secure by Letters Patent is:—

A hinge including a door member having an integral plate formed with a pivot boss and a shoulder, and a stationary member having an L-shaped slot, and a perforated 85 plate to receive the boss, whereby the door may be held open its full width by engagement of the shoulder with the wall of the slot.

FREDERICK A. LEDWARD.
